(57) **CLAIM**

The ornamental design for an optical disk storage rack, substantially as shown and described.

DESCRIPTION

FIG. 1 is a perspective view of an optical disk storage rack; FIG. 2 is a longitudinal cross sectional view of the optical disk storage rack, the opposite side being the same in appearance;

FIG. 3 is a front elevational view of the optical disk storage rack;

FIG. 4 is a top plan view of the optical disk storage rack shown with the top panel removed,

FIG. 5 is a perspective view of another embodiment of an optical disk storage rack, illustrating fewer storage racks; FIG. 6 is a longitudinal cross sectional view of the optical disk storage rack shown in FIG. 5, the opposite side being the same in appearance;

FIG. 7 is a front elevational view of the optical disk storage rack shown in FIG. 5;

FIG. 8 is a top plan view of the optical disk storage rack shown in FIG. 5 and shown with the top panel removed,

FIG. 9 is a perspective view of another embodiment of an optical disk storage rack, illustrating wider storage racks;

FIG. 10 is a longitudinal cross sectional view of the optical disk storage rack shown in FIG. 9, the opposite side being the same in appearance;

FIG. 11 is a front elevational view of the optical disk storage rack shown in FIG. 9; and,

FIG. 12 is a top plan view of the optical disk storage rack shown in FIG. 9 and shown with a top panel removed.
